HINGE MEANS

William M. Dwyer, Chicago, Ill., assignor to W. H. Miner, Inc., Chicago, Ill., a corporation of Delaware

Application October 19, 1939, Serial No. 300,218

15 Claims. (Cl. 16—163)

This invention relates to improvements in hinge means, and more particularly hinge means for removable floor racks of refrigerator cars.

One object of the invention is to provide hinge means for removable floor rack constructions for railway cars of the refrigerator type, hinged to the car walls in such a manner that the rack sections may be readily detached for removal from the car when desired, to convert the latter for lading which does not require elevation from the floor.

A further object of the invention is to provide in a construction of the character described in the preceding paragraph, rugged hinge means of simple design which is readily detachable from the car wall.

A still further object of the invention is to provide a floor rack structure hinged to the side wall of the car, wherein the hinge means is designed to be readily detached from its mounting on the car wall to permit removal of the rack from the car, and wherein both the hinge means and its mounting are secured to the rack and car wall, respectively, in such a manner as to require a minimum of fastening elements, thereby greatly reducing the cost per car both in labor and material.

Other objects of the invention will more clearly appear from the description and claims hereinafter following.

In the drawings forming a part of this specification, Figure 1 is a top plan view of a portion of the floor rack structure at one end of a refrigerator car, illustrating my improvements in connection therewith, the floor rack structure being broken away at one side of the longitudinal center line of the car, the car walls being shown partly in horizontal section and indicated in dotted lines. Figure 2 is a vertical sectional view, corresponding substantially to the line 2—2 of Figure 1, certain parts being shown in elevation, and the major portions of the floor rack section, side wall and floor of the car being broken away. Figure 3 is a vertical sectional view, corresponding substantially to the line 3—3 of Figure 2. Figure 4 is a vertical sectional view, corresponding substantially to the line 4—4 of Figure 2. Figure 5 is a view similar to Figure 2, illustrating another embodiment of the invention. Figure 6 is a horizontal sectional view, corresponding substantially to the line 6—6 of Figure 7, showing still another embodiment of the invention. Figure 7 is a view similar to Figure 2, illustrating the embodiment of the invention disclosed in Figure 6. Figure 8 is a vertical sec-

tional view, corresponding substantially to the line 8—8 of Figure 7. Figure 9 is a view similar to Figure 2 showing still another embodiment of the invention. Figure 10 is a vertical sectional view, corresponding substantially to the line 10—10 of Figure 9. Figure 11 is a view similar to Figure 2, illustrating a still further embodiment of the invention, the section being on the line 11—11 of Figure 13. Figure 12 is a horizontal sectional view, corresponding substantially to the line 12—12 of Figure 11. Figure 13 is a vertical sectional view, corresponding substantially to the line 13—13 of Figure 11. Figure 14 is a vertical sectional view, corresponding substantially to the line 14—14 of Figure 11.

In said drawings 20 indicates one end portion of a refrigerator car body, which is indicated by dotted lines in Figure 1. The car body is provided with the usual insulated walls, floor and roof, one of the side walls of said car being indicated by 21 and one of the end walls by 22. As is common practice, each wall is composed of spaced apart outer and inner wall members, the inner member of the side wall which is shown 10 in section in Figure 1 being indicated by 23 and that of the end wall being indicated by 24. One of the bulkheads or transverse partitions which 15 separates the ice compartment at the end of the car from the remainder of the car is indicated in 20 dotted lines and designated by 25. As is well understood by those skilled in this art, two such 25 bulkheads are provided in each car, one at each end thereof, and the space between the bulkheads 25 serves to accommodate the lading. When 30 the car is used for lading requiring elevation of the floor, the entire floor space between the bulkheads is covered by the floor rack structure. It 35 is common practice to employ a floor rack structure composed of a plurality of separate sections, 40 comprising two sets, the sets being divided lengthwise of the car and each set being divided transversely of the car into sections.

The floor rack as shown in Figure 1 comprises a plurality of similar sections 26—26, one of 45 which is illustrated substantially in full, but broken away transversely through the central portion to accommodate the same to the sheet of the drawings, other adjacent sections being shown broken away. The sections 26—26 are 50 arranged in sets at opposite sides of the center line of the car and cover the entire floor area which is available for lading. As is well understood, each complete set may be composed of any desired number of individual sections. Each section 26 comprises spaced transverse slats 27—27

secured to laterally spaced supporting beams or stringers 28-28. Each section 26 thus forms a unit and in accordance with my invention is arranged for bodily removal from the car.

Referring first to the embodiment of the invention illustrated in Figures 1 to 4 inclusive, each floor rack section 26 is connected to the corresponding wall 21 of the car by improved detachable hinge means, indicated broadly by A, which support the rack section along the outer edge at a plurality of points for swinging movement, the hinge means being directly supported on and connected to the inner wall member 23 of said side wall 21.

My improved supporting hinge means A comprises broadly a supporting keeper or socket B fixed to the wall member 23; a hinge butt C secured to the floor rack; and a hinge arm D pivotally connected to the hinge butt and detachably connected to the supporting keeper B.

The keeper B is preferably in the form of a casting having laterally extending securing ears 29-29. The keeper is seated in a recess provided in the wall member 23, as clearly shown in Figure 2, and is secured in place and fixed to the wall member 23 by bolts 30-30 or similar securing elements extending through the ears 29-29 and said side wall member, the ears 29-29 being set into the wall and pocketed to accommodate the nuts of the bolts, so that the same will not project beyond the inner surface of the wall member 23. The keeper member B, which is in the form of a socket, as shown in Figures 2 and 3, has top and bottom walls 31 and 32, front and rear walls 33 and 34, and side walls 35-35. The top and bottom walls 31 and 32 are substantially horizontally disposed, and the outer or forward end of the bottom wall provides a round abutment shoulder 36 where it merges with the front of the keeper. The front wall 33 is cut away at the lower portion of the keeper to provide a relatively wide opening 37 which corresponds in width to the interior of the socket member of the keeper. The wall 33 is centrally, vertically slotted, as indicated at 38, to accommodate the hinge arm D, as hereinafter will appear.

The hinge butt member C, as most clearly shown in Figures 2 and 4, comprises an elongated plate member 39 having upstanding and laterally, outwardly projecting hinge ears 40-40 thereon. The hinge ears 40-40 are spaced laterally apart, as shown, to accommodate the hinge arm D therebetween and are perforated to receive the hinge pin. The plate member 39 of the hinge butt C is secured to the outer vertical face of the outermost stringer 28 of the rack section 26 by a pair of bolts 41-41 extending through said plate 39 at opposite ends thereof and through said stringer 28. The hinge butt is so positioned that the ears 40-40 thereof closely underlie adjacent slats 27-27 of said rack section with the opening between said ears aligned with the opening between said adjacent slats. As shown most clearly in Figure 4, the width of the opening between the ears 40-40 is substantially the same as the space between the adjacent slats 27-27.

The hinge arm D is in the form of an elongated, angular, flat, barlike member reinforced at opposite sides along its edges by ribs 42-42. The inner end of the arm D extends between the ears 40-40 of the hinge butt C and is pivotally connected to said butt member by a pin 43 ex-

tending through the hinge pin receiving openings of the ears and said end of the arm.

The opposite or outer end of the arm D is provided with oppositely extending, transversely aligned, lateral lugs 44-44, which are preferably of cylindrical cross section and are adapted to be engaged within the keeper member B in back of the front wall 33 to anchor said arm to the side wall of the car. As shown most clearly in Figure 2, the arm D is enlarged in width between its ends, thereby providing a depending portion 45 formed with a shoulder 46 adapted to seat on the shoulder 36 of the keeper B to lock said arm against downward swinging movement toward the side wall of the car when the arm is anchored to the keeper by the lugs. The arm D is of such a thickness that it passes freely through the slot 38 of the front wall of the keeper B and the lugs 44-44 of said arm are designed to pass freely through the opening 37. As will be evident, when the hinge member is anchored to the keeper B, as shown in Figures 1, 2, and 3, the arm D is maintained in fixed position at all times and especially during swinging movement of the rack section on the pivotal hinge member, by the lugs 44-44 of said arm being engaged in back of the front wall of said keeper and in abutment with the top wall of said keeper, and the shoulder 46 of said arm abutting the shoulder 36 of the keeper, the weight of the rack being sustained by the inner or hinged end of said arm holding the latter in shouldered engagement with the shoulder 36 of the keeper and pressing the lugs 44-44 upwardly against the top wall of the keeper and outwardly against the front wall of the same.

As shown in Figure 1, each floor rack section 26 is supported by the hinge means A in such a manner that it is reliably anchored to the car wall for swinging movement on its hinged axis, either from horizontal to vertical position or from vertical to horizontal position. The vertical position of said rack section is indicated in dotted lines in Figure 2.

A plurality of hinge means A are preferably provided for each rack section, the members thereof being spaced along the outer edge of said section. Any suitable number of hinge means A may be employed to properly support the rack. As will be obvious, the supporting keeper members B employed necessarily correspond in number to the hinge means.

When it is desired to convert the car for service for lading which does not require elevation from the floor, the rack sections 26-26 are detached and completely removed from the car, thereby making available the maximum lading capacity of the car. In detaching the different rack sections it is necessary merely to raise or lift the side of each section adjacent the wall of the car so that the arm D of the hinge means may swing or drop downwardly until the lugs 44-44 thereof come into alignment with the opening 37 of the corresponding keeper member, and then pull the rack section away from the side wall of the car, the lugs 44-44 thus passing through said opening, thereby entirely disconnecting the hinge arm from the keeper member. The rack section after being thus detached from the car wall is ready for complete removal from the car.

To replace the rack section the reverse procedure is followed, the lugs 44-44 of each hinge means A being entered through the opening 37 of the keeper B and engaged in back of the

front wall of said keeper at opposite sides of the slot 38, the lugs 44-44 being passed through said opening 37 while the side of the rack adjacent the wall of the car is raised to a proper extent above the floor. As will be evident, when the rack section is subsequently lowered onto the floor, the outer end of the arm D is thrown into engagement with the shoulder 36 of the keeper B, thereby camming the arm upwardly and bringing the lugs 44-44 into the position shown in Figure 2, engaged behind the front wall 33 of the keeper and bringing the shoulder 46 of the arm D into abutting relation with the shoulder 36 of the keeper.

Referring next to the embodiment of the invention illustrated in Figure 5, a hinge means and cooperating keeper member similar to and operating in substantially the same manner as the hinge means and keeper disclosed in Figures 1, 2, 3, and 4, is shown, but differing from the latter in that additional means is employed for positively preventing disengagement of the hinge arm from the keeper.

As shown in Figure 5, the detachable hinge means comprises a keeper member, a hinge butt, and a hinge arm, corresponding to the keeper member B, hinge butt C, and arm D of Figures 1 to 4 inclusive, and also indicated respectively by B, C, and D. The different parts of the keeper B, hinge butt C, and the arm D are indicated in Figure 5 by the same characters as employed for the corresponding parts in Figures 1 to 4 inclusive.

The pocket of the keeper member B shown in Figure 5 is of greater vertical height than the pocket of the keeper shown in Figures 1 to 4 inclusive and has a bolt 47 extending into the same through the back wall 34 thereof, this bolt being engaged through the inner wall member 23 of the side wall of the car and projecting a short distance into the socket of the keeper. This bolt 47 is provided with a nut 48 which is threaded on said projecting end. The bolt 47 is so positioned that the nut 48 thereof, when threaded on said bolt, acts as a stop to limit downward displacement of the trunnions 44-44 of the arm D to an extent which will prevent the lugs from clearing the lower edge of the wall 33 of the keeper, thus preventing these lugs from being brought into position to pass through the opening 37 of the keeper to be disengaged from the latter. The position of the bolt, however, does not prevent disengagement of the arm D from the pocket of the keeper when the nut is removed, sufficient clearance being provided between the threaded end of the bolt and the lower edge of the front wall 33 of the keeper to permit downward passage of the lugs 44-44 therebetween. As will be evident, so long as the nut 48 is in place on the bolt 47, detachment of the hinge means from the socket is precluded, and when it is desired to remove the rack all that is required is removal of this nut to permit disengagement of the hinge means in the manner hereinbefore described in connection with the structure disclosed in Figures 1 to 4 inclusive.

Referring next to the embodiment of the invention disclosed in Figures 6, 7, and 8, a hinge means, similar to the hinge means hereinbefore described in connection with Figures 1 to 4 inclusive, is shown comprising a hinge butt and hinge arm substantially the same as the hinge butt C and the hinge arm D described in connection with Figures 1 to 4 inclusive and also indi-

cated by C and D, respectively, and a hinge keeper E of different design. In Figures 6, 7, and 8 the different parts of the hinge butt C and the hinge arm D are indicated by the same characters as the corresponding parts in Figures 1 to 4 inclusive.

The keeper E is in the form of a substantially circular cap, seated in a recess in the inner face of the inner wall member 23 of the side wall of the car. The rear or inner wall of the cap is indicated by 49. The wall 49 is provided with a projecting central boss 50 which is internally threaded. The keeper E is fixed to the wall member 23 by a single bolt 51 which extends through said wall 23 and is threaded into the boss 50 of said keeper. The front wall of the keeper E is provided with a cruciform slot 52 having the arms of the cross disposed respectively horizontally and vertically. As shown, the horizontal portion of said slot, which portion is indicated by 53, is of greater length than the vertical portion thereof, which is indicated by 54. The portion 53 of the slot is of such a size as to permit the lugs 44 of the arm D to pass freely therethrough, and the vertical portion 54 is of such a width as to freely accommodate the outer end portion of the arm D. The hinge arm D is anchored to the keeper E and disengaged from the same in the same manner as the arm D of the device shown in Figures 1 to 4 inclusive is engaged with and disengaged from the keeper B, to connect the rack section to the car and remove the same therefrom.

Referring next to the embodiment of the invention illustrated in Figures 9 and 10, a hinge means of a design somewhat similar to the hinge means shown in Figures 1 to 4 inclusive is disclosed and which operates in substantially the same manner, the only difference being that a keeper of a different design than the keeper B of Figures 1 to 4 inclusive is employed. The structure shown in Figures 9 and 10 comprises a keeper member F seated in the side wall of the car, a hinge butt secured to the rack 26, and a hinge arm connected to said butt and anchored to the keeper, said hinge butt and hinge arm being similar to the hinge butt C and the hinge arm D hereinbefore described in connection with Figures 1 to 4 inclusive and being also respectively indicated by C and D.

In Figures 9 and 10 the different parts of the hinge butt C and the arm D are indicated by the same reference characters as used for the corresponding parts in Figures 1 to 4 inclusive.

The keeper member F is in the form of a circular cap seated in a recess in the inner side of the wall member 23 of the car. The back wall of the keeper F, which is indicated by 55, is provided with a central, inwardly projecting boss 56. The boss 56 is interiorly threaded to receive the threaded end of a bolt 57 by which the keeper is secured to the wall 23. The bolt 57 extends through the side wall 23 of the car and the boss 56, the threaded end thereof projecting within the pocket of the keeper beyond the boss 56. A nut 58 threaded on the projecting end of said bolt prevents disengagement of the lugs 44-44 from the keeper F in the same manner as the nut 48 of the bolt 47 disclosed in connection with Figure 5 prevents disengagement of the lugs 44-44. The front wall of the keeper member F, which front wall is indicated by 59, is provided with a cruciform slot 60, the crossing sections of which are of the same length. Each of the sections of the slot 60 is of a width to either freely accommodate

the outer end of the arm D or permit free passage of the lugs 44—44 of said arm therethrough. It will thus be seen that the keeper member F will be in operative position to have the arm D anchored thereto regardless of which portion of the slot 60 is disposed horizontally, both portions of the slot permitting the lugs 44—44 to pass therethrough. In securing the keeper member F in position, the bolt 57 is first engaged through the wall 23, as indicated in Figure 9, and the keeper member is then screwed onto the bolt until it is drawn and clamped tightly against the inner wall of the recess within which it fits. In the event that either portion of the cruciform slot 60 is not disposed horizontally when the keeper is clamped against the inner wall of the receiving recess, it will require less than a quarter turn to bring the other portion of said slot to true horizontal position, and slight tightening only of the keeper is necessary to permit the required rotation of the keeper on the threads of the bolt. It will thus be evident that the cruciform arrangement of slot provides for a latitude of adjustment which will permit tight clamping of the keeper in its seat under any conditions. To permit application and removal of the stop nut 58, the inner corners of the walls defining the slot 60 are cut away, as indicated at 61—61, to provide an opening larger than the circumference of said nut.

Referring next to the embodiment of the invention illustrated in Figures 11 to 14 inclusive, my improved detachable hinge means for the floor rack section comprises broadly a keeper member G set into the side wall of the car; a hinge butt H; and a hinge arm K.

The keeper member G is preferably in the form of an elongated casting provided with a pocket 62 opening through the front wall of the keeper, as indicated at 63. This pocket is located between the ends, slightly off center with respect to the length of said casting, as seen in Figure 13, the displacement being to the left of the center. A cylindrical bore or seat 64 parallel to the length of said casting opens into the pocket 62 at the left hand side of the latter, as seen in Figure 13. The seat 64 is preferably spaced slightly from the top and bottom walls, respectively, of said pocket, as clearly indicated in Figure 11. At opposite sides of the pocket 62, the casting is provided with outwardly opening seats 65—65 adapted to accommodate the nuts of the bolts by which the casting is secured to the wall 23, as hereinafter pointed out. The keeper casting G is seated in a suitable recess in the wall 23, this recess being of such a depth that the front face of the casting is flush with the inner face or surface of the wall 23. A pair of bolts 66—66 extending through the wall 23 and opposite ends of said casting into the seats 65—65 serve to secure the keeper casting to the wall 23, the casting being secured by nuts threaded on said bolts and accommodated in the seats 65—65.

The hinge butt member H comprises an elongated plate section 67 provided with a pair of upstanding, laterally, outwardly projecting hinge ears or lugs 68—68 at the central portion thereof, the lugs being spaced laterally apart a distance corresponding to the spacing between two adjacent slats 27—27 of the rack section 26. As clearly shown in Figure 14, the opening between the lugs 68—68 register with the opening between said adjacent slats. The platelike section of the hinge butt is provided with horizontally

disposed slots 69—69 at opposite ends thereof, which slots are in horizontal alignment. The hinge butt H is secured to the vertical outer face of the outermost slat 28 of the rack section 26 by bolts 70—70 extending through said slat and the slots 69—69 of the plate section of the hinge butt. As shown, the threaded ends of the bolts extend through the slots 69—69 and nuts 71—71 are threaded on said ends to clamp the hinge butt in fixed position. As will be evident, when the nuts 71—71 are loosened the hinge butt may be slid from right to left, as viewed in Figure 14, the slots 69—69 permitting such adjustment.

The hinge arm K is in the form of a relatively wide bar having reinforcing ribs 72—72 along its outer edges. The inner end of the arm K is pivotally connected to the ears 68—68 of the hinge butt H by a pivot pin 73 extending through said ears and the arm. As shown most clearly in Figure 14, the arm K is engaged between the ears 68—68 and is in alignment with the opening between the adjacent slats 27—27 of the rack section 26 when the hinge butt H is in the position shown in said figure, so that the arm may swing freely between said slats. The outer or left hand end of the arm K, as seen in Figure 11, is provided with a laterally projecting lug 74 on one side thereof, said lug, as shown in Figures 12 and 13, being on the left of the arm. The lug 74 is of cylindrical cross section and of a size to be accommodated in the seat 64. This lug provides, in effect, a hook on the outer end of the arm which is engaged within the keeper member G to anchor the floor rack section to the side wall of the car. This hooked end of the arm K is of such a size that it will pass freely through the opening 63 of the pocket 62 of the keeper member G so that it may be readily entered into said pocket of the keeper for engagement of the lug 74 with the seat 64 and withdrawn from said pocket after disengagement of the lug from the seat.

The same means is employed as disclosed in Figures 1 to 4 inclusive to hold the arm K in the position shown in Figure 11 and prevent downward swinging movement thereof on the lug 74, the arm K being provided with a shoulder corresponding to the shoulder 46 of the arm D and also indicated by 46, and the keeper G being provided with a shoulder corresponding to the shoulder 36 of the keeper B and also indicated by 36. As will be evident, with the parts disposed, as shown in Figures 11 to 14 inclusive, the rack section is securely anchored to the car wall and is swingable on the pivotal connections between the arms K—K and the hinge butts H—H of the several hinge means employed to move the rack from the full line horizontal position shown in Figure 11 to the vertical position shown in dotted lines in said figure, or swing the same in the reverse direction.

To remove the rack section, the nuts 71—71 of the bolts of each hinge butt H are first loosened. The hinge butts are then slid to the left, as seen in Figure 14, and inasmuch as the hinge arm K is pivotally connected to the hinge butt between the ears 68—68 thereof, this arm will be moved laterally with the hinge butt, thereby effecting disengagement of the lug 74 from the seat 64 of the keeper G. After the lug has been thus disengaged, the rack section is pulled away from the side wall of the car, thus withdrawing the arm K from the corresponding keeper G, the hooked end of the arm K passing freely through the opening of the keeper, as hereinbefore pointed out.

ed out. The rack section which has thus been disconnected from the side wall, by lateral adjustment of all of the hinge butt members H of said rack section, may then be completely removed from the car.

In connecting the rack sections to the side wall of the car, the operation is substantially the reverse of that described, the hinge butt H of each hinge means being first adjusted so that the arm K, which is hinged thereto, is positioned with the hooked end thereof in registration with the opening of the pocket 62 of the corresponding keeper G. After so adjusting all of said hinge butts of the section, the latter is pushed toward the side wall of the car to enter the hooked ends of the arms K—K into the pockets of the keepers. Each hinge butt is then slid from left to right, as viewed in Figure 14, to bring the same to the position shown in said last named figure and seat the lug 74 of the arm K within the seat 64. Each hinge butt H is then locked in its adjusted position by tightening the nuts 71—71 of the bolts 69—69.

In this connection it is pointed out that when all of the rack sections forming the complete floor rack have been thus applied to the car, the hooked ends of the hinge arms cannot become disengaged from the keepers by displacement of said hooked ends from their seats, because, due to engagement of the assembled rack sections with each other, sliding movement of each individual rack section lengthwise of the car with resultant similar displacement of the hinge arms is positively prevented.

I have herein shown and described what I now consider the preferred manner of carrying out my invention, but the same is merely illustrative and I contemplate all changes and modifications that come within the scope of the claims appended hereto.

I claim:

1. In a floor rack structure including a separate rack section for a refrigerator car having a side wall, the combination with a socketed keeper secured to said side wall; of a hinge arm pivoted at one end to said rack section, said arm having a laterally projecting lug at the other end detachably engageable with said keeper; and a shoulder on said arm having shouldered engagement with said keeper to hold the arm against downward swinging movement about said lug.

2. In means for swingingly supporting a member, the combination with a fixed keeper, said keeper having a socket provided with a vertically slotted front wall, said socket being open below said front wall; a hinge butt secured to said member; a hinge arm pivoted at one end to said hinge butt and having lugs at the other end engageable in back of said front wall of the socket with the adjacent portion of said arm accommodated in said slot; and a depending abutment portion on said arm having shouldered engagement with the keeper below said front wall thereof to hold said arm against downward swinging movement with respect to said keeper.

3. In hinge means for a swingable rack, the combination with a hinge butt adapted to be fixed to said rack; of a hinge arm pivotally connected at one end to said hinge butt for swinging movement in a vertical plane, said arm having oppositely projecting anchoring lugs at the other end; and a fixed keeper, said keeper having a vertical front wall and an entrance opening below said wall, said front wall being vertically slotted to accommodate the second named

end of the arm with the lugs of said arm engaged in back of said wall, said arm having a depending portion in shouldered engagement with the keeper to support said arm against swinging movement with respect to the keeper and maintain said lugs in shouldered engagement with said front wall, said depending portion of said arm being disengaged from the keeper when the rack and attached hinge butt are lifted to permit said arm to swing downwardly under the influence of gravity to disengage the lugs from said front wall of the keeper.

4. In hinge means for swingingly supporting a member from a vertical wall, the combination with a keeper fixed to said wall; of a vertically swingable hinge arm pivoted at one end to said member, said arm having means at the other end thereof for detachably anchoring the same to the keeper; and a shoulder on said keeper for supporting said arm to hold said means anchored to the keeper, said arm being slidable on said shoulder by raising of the pivoted end of the arm to disengage said anchoring means from the keeper.

5. In hinge means for swingingly supporting a member from a vertical wall, the combination with a keeper secured to said wall, said keeper having a socket provided with a front wall and an opening below said front wall; of a hinge arm pivoted at one end to said member, said arm having an anchoring lug at the other end engaged in back of said front wall of the keeper, said second named end of the arm being movable through said opening to engage said lug and disengage the same from the keeper; a bolt for attaching the keeper to said vertical wall, said bolt extending into said socket and projecting toward said front wall of the keeper, said projecting end of the bolt being spaced from said keeper wall a distance to not obstruct passage of said second named end of the arm through said opening of the keeper; and a nut removably threaded on said projecting end of the bolt and restricting the space between said bolt and front wall of the pocket to an extent to prevent passage of said second named end of said arm.

6. In hinge means for supporting a member from a wall, the combination with a hinge arm pivoted at one end to said member; of a keeper engaging anchoring head at the other end of said arm; a keeper with which said head is engageable, said keeper being in the form of a cylindrical cap; and a single fastening element for said cap, disposed axially thereof and extending through said wall.

7. In hinge means for swingingly supporting a member from a wall, the combination with an arm hinged at one end to said member; of a keeper engaging anchoring head at the other end of said arm; a cylindrical cap-shaped keeper seated in said wall, said cap having an inner wall provided with a central threaded opening; and a securing bolt having threaded engagement with said opening for clamping the keeper to said wall.

8. In hinge means for swingingly supporting a member from an upright wall, the combination with a hinge arm pivoted at one end to said member, said arm having laterally projecting securing lugs at the other end; of a cap-shaped keeper having back and front walls, said front wall being provided with a cross-shaped slot comprising sections intersecting at right angles, each of said sections of the slot being of an

overall length to freely admit said lugs, and of a width to admit said arm; and means securing said socket to said upright wall.

9. In hinge means for swingingly supporting a member from an upright wall, the combination with a cylindrical cap-shaped keeper having front and rear walls, said rear wall being provided with a central opening which is internally threaded, said front wall having intersecting slots therethrough forming a cross; of a single clamping bolt extending through said upright wall member and having the threaded end thereof screwed into said threaded opening; an arm hinged at one end to said member; and laterally projecting lugs at the other end of said arm, said arm being of a thickness less than the width of the opening of either of said slot sections, and said lugs being of a size to pass freely through the openings of either of said slot sections.

10. In hinge means for swingingly supporting a member from a vertically disposed wall, the combination with a keeper secured to said wall; of a hinge butt; an arm pivoted at one end to said butt and having a laterally projecting hook-shaped head at the other end engageable with said keeper by lateral displacement of said arm; and means for adjustably clamping said hinge butt to said member.

11. In hinge means for swingingly supporting a member from a vertically disposed wall, the combination with a keeper fixed to said wall; of a hinge butt having a base which is horizontally slotted; a bolt engaged through said slot for adjustably clamping said hinge butt to said member; and an arm hinged at one end to said hinge butt and having the other end laterally hooked for engagement with said keeper.

12. In hinge means for swingingly supporting a member from a vertically disposed wall, the combination with a floor rack section; of a keeper secured to said wall, said keeper having an outwardly opening pocket having interior side walls, one of said side walls having a horizontally disposed seat opening laterally into said pocket; a hinge butt having a platelike base portion provided with horizontal slots; securing bolts extending through said slots for adjustably securing said hinge butt to said member; and an arm pivoted at one end to said hinge butt, the other end of said arm extending into the pocket of the keeper and having a horizontally disposed, laterally projecting lug thereon engaged in said seat.

13. In hinge means for swingingly supporting a rack from a vertical wall to be folded against said wall in upright position, the combination with a keeper adapted to be fixed in said wall,

said keeper having a seat provided with downwardly and inwardly facing shoulder portions; of a hinge arm to one end of which said rack is pivotally connected to swing to said upright position, said arm having a laterally projecting horizontal lug at the other end detachably engaged underneath said downwardly, and in back of said inwardly facing shoulder portions of said keeper; and a shoulder on said arm below and outwardly of said lug in shouldered engagement with the keeper below the point of engagement of the lug with said shouldered portions of the keeper to hold the arm against downward swinging movement on said lug in laterally extended position with respect to said wall while said rack is swung to said upright position, said arm pivoting on its shouldered engagement with the keeper when the inner end of the rack is lifted to thereby disengage the lug from said inwardly facing shouldered portion of the keeper.

14. In hinge means, the combination with a hinge butt; of a keeper secured in fixed position; a hinge arm; pivot means hingedly connecting said hinge butt to one end of said arm, said arm having anchoring lugs at the other end, said keeper having an opening through which said second named end of the arm may pass to bring the lugs thereof into shouldered engagement with the keeper; and stop means for preventing removal of said lugs from shouldered engagement with the keeper, including a detachable element blocking the passage of said second named end of the arm through the opening of the keeper.

15. In hinge means for hinging a floor rack, normally resting on a floor, to a vertical wall, the combination with a vertically disposed keeper secured to said wall; of a supporting shoulder at the lower end of the keeper; a vertically disposed front wall on said keeper having its bottom edge above said shoulder in spaced relation thereto; an arm hinged at one end to said floor rack to permit swinging movement of the latter on said arm to upright position alongside said wall; and an anchoring lug at the other end of said arm in shouldered engagement with the back of said front wall of the keeper, said arm at said last named end being supported on said shoulder against downward swinging movement on said lug, said arm being swingable with respect to the rack when the latter is lifted at its inner edge to position said last named end of the arm together with said lug to pass freely through the opening of said keeper between said shoulder and the lower edge of said front wall of the keeper.

WILLIAM M. DWYER.
